Kathleen A. Costigan(57) **CLAIM**

The ornamental design for a timer, as shown and described.

DESCRIPTION

FIG. 1 is a front perspective view of a timer showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken-line disclosure of elements in the views are understood to be functional aspects of the article in which the design is embodied and form no part of the claimed design.

1 Claim, 4 Drawing Sheets**FIG. 1**
